CEILING DOME FOR A HANGING LAMP

Sam De John, 4604 SW. 31st Drive,
Hollywood, Fla. 33023

Filed Dec. 15, 1971, Ser. No. 208,509

Term of patent 14 years

Int. Cl. D26—05

U.S. Cl. D48—7 D

FIG. 1 is a perspective view of a ceiling dome for a hanging lamp showing my new design.

FIG. 2 is an elevational view of the dome on an enlarged scale.

FIG. 3 is a top plan view thereof.

FIG. 4 is a cross-sectional view taken on line 4—4 of FIG. 3.

I claim:

The ornamental design for a ceiling dome for a hanging lamp, as shown.
